UNITED STATES PATENT OFFICE.

PETER ALBERT HOFFMAN, OF HASTINGS, MINNESOTA.

FOLDING BOX.

1,339,339.

Specification of Letters Patent.

Patented May 4, 1920.

Application filed July 26, 1919. Serial No. 313,458.

To all whom it may concern:

Be it known that I, PETER A. HOFFMAN, a citizen of the United States, and a resident of Hastings, in the county of Dakota 5 and State of Minnesota, have invented a new and Improved Folding Box, of which the following is a description.

My invention relates to folding or knock-down boxes and more particularly to a folding 10 box used for the mailing of currency and valuable securities, such as bonds, notes, mortgages, etc.

The general object of the invention is to provide a folding box of the indicated type 15 which can be variously folded to produce different capacities of receptacle whereby the box may be made to exactly and tightly fit its contents.

A further important object of the invention 20 is to provide for the proper sealing of the ends of the package to thereby overcome a defect in and annoyance attending the use of packages of the form now generally used, the end sealing of which falls far short of 25 what is desirable.

More specifically, the invention has for its object to carry out the principle of the variable size of the box in such manner and by such means as to permit of the box being 30 given the particular size desired quickly and with facility and promote convenience in the folding and sealing of the box.

Reference is to be had to the accompanying drawings forming a part of this specification, it being understood that the drawings are merely illustrative of practical examples of the invention.

Figure 1 is a plan view of a box in knocked down form;

40 Fig. 2 is a side elevation with the body of the box folded but with the sealing wrapper unfolded;

Fig. 3 is a perspective view of the box completely folded and sealed, part of the 45 wrapper being broken away;

Fig. 4 is a view similar to Fig. 1 but illustrating the preferred form of the invention with respect to the wrapper which is provided with members for the proper sealing 50 of the ends of the package.

Fig. 5 is a perspective view of the box shown in Fig. 4 but folded and partially sealed, the final sealing flap shown ready to be positioned.

55 Referring more particularly to the form

of the invention illustrated in Figs. 1 to 3, the box is formed with two crossing strips or sheets, 10, 11, of light cardboard. The box presents a central panel 12 which I term the body panel and which forms one side of 60 the box, advantageously the face. The box has applied to it a wrapper 13 along three sides of which mucilage or other adhesive is applied as indicated at 13^a.

The numeral 14 indicates the end panels 65 which are integral with the main panel and foldable relatively to the latter on the score line 14^a. Integral with the end panels 14 are foldable flaps 15 adapted to fold over the back of the box or side opposite the 70 panel 12 and said flaps 15 are integral with the end panels 14. The numeral 16 indicates narrow panels, three being shown in the

present instance joining each flap 15 with an end panel 14, said panel 16 being defined by score lines 17. The arrangement is such that the material may be folded on either of the lines 17, so that one or more of the adjusting panels 16 may be made part 75 of either the adjacent end panel 14 or the 80

adjacent flap 15 to vary the relative sizes of the end panels and their associated flaps. Thus, each end panel may be given an area equaling the end panel 14 or said panel plus one or all of the panels 16 or, on the other hand, a folding end flap may have included in its area one or all of the panels 16 leaving the ends of the box to be formed solely by the end panels 14. The height of the box can thus be made to correspond with the 85 height of the folded end panels 14 or these panels plus one or more of the panels 16.

Similarly, the side panels 18 which are joined to the main body panel 12 are integral with flaps 19, foldable to form the back 90 of the box or that face opposite the main panel 12, there being intermediate narrow panels 20 defined by the score lines 21, whereby one or more of the panels 20 may be made to form with the group of panels 18 the sides 95 of the box, or on the other hand any or all of the panels 20 may be made to form with the flaps 19 the back of the box or that face opposite the body panel 12. The panels 14 and 18 are of corresponding width and the 100 score lines 21 defining the panels 20 have the same relation to the panel 18 that the score lines 17 have to the end panels 14, whereby the respective score lines at the sides and ends and the panels defined there-

by may be made to aline when the material is folded on the corresponding score lines at the sides and ends so that the sides of the box and the ends may readily be given corresponding height in adjusting the box to possess a given capacity.

In addition to the score lines 17 and 21 and the panels defined thereby, I form the free edge of the flaps 19 with a plurality of score lines 23 parallel with the score lines 21 and defining narrow panels 22. Thus, the material may be folded on either of the score lines 23 to conform to a given height or thickness of box produced by folding on particular score lines 17, 21. If the box be made of the maximum thickness, that is to say, with the sides formed jointly by the panels 18 and all the narrow panels 20 as in Fig. 2, then the panels 22 will remain in the plane of the flaps 19 in forming the face of the box opposite the body panel 12. If the box be of the minimum thickness, that is to say, with the sides and ends of the box of a height represented by the width of the panels 14, 18, all the panels 16 and 20 will fold with the flaps 15 and 19 to form the face of the box opposite the main panel 12 and in that case the side flaps 19 and the panels 20 will equal the width of the panel 12 and completely form that face of the box opposite said panel 12. In this case the material will be folded on the innermost score lines 23 so that the panels 22 will be folded down at the sides of the box to overlap said sides.

In Fig. 3, at the left, I have indicated the box so folded that only one panel 20 jointly forms with the adjacent panel 18, the side of the box, the remaining panels 20 being folded over to lie in the plane of the flap 19 at a face of the box. In this case two panels 22 fold down at the adjacent side of the box while the other panels 22 remain in the plane of the flap 19. While in Figs. 2 and 3 I have shown the differently adjusted boxes with sharp angles at the panels 20, 22, it will be readily understood that in practice, in drawing the foldable panels and flaps tightly over the packet of currency or like material, the side edges of the packet will be pressed down out of really square form so that the box may not be squared when adjusted, from which it will be readily understood that more or less of the panels 20 will be drawn into the plane or approximate plane of the flap 19 and more or less of the panels 22 will be drawn down or partially down over the adjacent side of the box. In fact, it will be evident that the provision of the adjusting panels and their defining score lines provide a means lending to the foldable members a superior flexibility at the areas provided between the respective end and side panels and the flaps associated therewith to per-

mit of the ready bending of the foldable members along lines to produce a receptacle of the desired capacity.

The wrapper 13 is entirely free from the foldable panels and flaps, being initially gummed only to the body panel 12. After the various foldable panels and flaps have been folded to produce a box of a given size, said wrapper, which in Figs. 1 to 3 is of plain rectangular form, as indicated in Fig. 3 and the ends may, as shown, be sealed with wax or equivalent sealing material as indicated at 13^b, Fig. 3.

In the form of the invention illustrated in Figs. 4 and 5 which is preferred, the wrapper 13^b corresponds in general with the wrapper 13 in that it is provided along the side edges with adhesive material to constitute said side edges, adhering members 13^c, said edges extending beyond the sides of the stripping 10^a as in the first construction and in addition I provide laterally projecting flaps 13^d having adhesive material thereon and positioned at the ends of the wrapper so that when the wrapper is folded about the sides of the box, said flaps 13^d may be folded downward over the ends of the package against the outer faces of the end panels 14^a, the adhesive side portions 13^c being folded either at the inside of the flaps 13^d, or outside of the same as in Fig. 5. Finally, there is a flap 13^e with adhesive material extending outside of and in the same direction as the panels 14^a, 15^a corresponding with the portions 14, 15 in the first construction. The flap 13^e is of a sufficient width to overlie the previously folded and adhering members 13^c, 13^d, so as to effectively and neatly seal the end of the package. In addition the flap 13^e is of sufficient length to overlie one of the sides of the package as shown at the left in Fig. 5, thus producing a locking action which will assist in producing not only a tight sealing action, but a retaining action. In the form shown in Figs. 4 and 5 the various panels and related members are similar to the corresponding features in the first construction except as to their relative proportions. Therefore, I have designated those panels, fold-over flaps, and score lines corresponding respectively with the similar elements in the first construction, by the same reference characters but having exponents. The dotted lines 13^f and the full lines 13^g, 13^h, Fig. 4, indicate the defining lines of the ungummed area of the wrapper 13^b, the defining lines of the ungummed area, Fig. 1, being indicated by the character 13ⁱ.

I would state in conclusion that while the illustrated example constitute practical embodiments of my invention, I do not limit myself strictly to the mechanical details herein illustrated, since manifestly the same can be considerably varied without depar-

ture from the spirit of the invention as defined in the appended claims.

Having thus described my invention, I claim as new and desire to secure by Letters

5 Patent:

1. A folding receptacle of the class described having a body panel constituting one face of the box, foldable unscored panels extending laterally from the body panel 10 at the four sides to form the main area of the sides and ends of the receptacle, fold-over flaps united to the side and end panels to constitute the opposite face of the box, and a plurality of narrow panels connecting the said flaps with the respective side and end panels, there being score lines defining said narrow panels to adapt the latter to form part either of the flaps or the adjacent panels, there being additional 15 score lines adjacent to the free ends of the turn-over flaps and distant from those score lines adjacent to the side panels, said additional score lines dividing the edge portion into a plurality of small panels, any 20 of which may be folded down onto the adjacent side panel when the flaps are folded over.
2. A folding receptacle of the class described having a body panel constituting 30 one face of the box, foldable unscored panels extending laterally from the body panel at the four sides to form the main area of the sides and ends of the receptacle, fold-over flaps united to the side and end panels to 35 constitute the opposite face of the box, and a plurality of narrow panels connecting the said flaps with the respective side and end panels, there being score lines defining said narrow panels to adapt the latter to form 40 part either of the flaps or the adjacent panels, there being additional score lines adjacent to the free ends of the turn-over flaps and distant from those score lines adjacent to the side panels, said additional 45 score lines dividing the edge portion into a plurality of small panels, any of which may be folded down onto the adjacent side panel when the flaps are folded over; together with a wrapper for said receptacle 50 and of greater width than the same at the body panel, side panels, and flaps to present side portions therebeyond, said side portions having adhesive material applied thereto and extending at the sides of the 55 score lines including certain of the score lines adjacent to the free edges of the flaps.
3. A foldable box including panels foldable to form the various sides of the box, and a wrapper therefor extending at the 60 sides beyond the side edges of the box members and having adhesive material thereon;

together with sealing flaps at the side edges of the wrapper and positioned respectively adjacent to the ends of the wrapper and the center thereof, those portions of the 65 wrapper having the end flaps and center flaps presenting with said flaps a greater width than the portions between the center and end flaps, and said center flaps extending 70 beyond the end flaps.

4. A knockdown receptacle including foldable members to form the various sides and ends of the box, and a wrapper therefor having sealing flaps projecting from the wrapper at the side edges adjacent to the 75 ends, and a larger sealing flap projecting from the side edges of the wrapper at the approximate center to correspond in position with the positions of the end members of the box, the intermediate portions of the 80 wrapper, between the center and end flaps, being of a width to lie within the outer edges of the flaps.

5. A knockdown receptacle including 85 foldable members to form the front, back, sides and the ends of the box, and a wrapper therefor of greater width than those members of the box constituting the top, bottom and sides of the box, said wrapper having adhesive material extending longitudinally at the side edges at both sides of the end members, together with sealing flaps for the ends of the box, said flaps being disposed respectively adjacent to the 90 ends of the wrapper at the sides thereof and 95 extending beyond the first-mentioned adhesive areas, and central sealing flaps on the wrapper corresponding in position with the end flaps of the box and adapted to be sealed over the other flaps when the latter 100 are folded onto and caused to adhere to the ends of the box.

6. A knockdown receptacle including foldable members to form the front, back, sides, and ends of a box, and a wrapper therefor of 105 greater width than the width of those portions of the box constituting the front, back, and sides of said box, said wrapper having adhesive material extending longitudinally at the side edges thereof at both sides of the 110 foldable end members of the box; together with sealing flaps on said wrapper for the ends of the box, said sealing flaps being disposed between and extending beyond said side edge portions of the wrapper and 115 of substantial the same width as the box when folded and of a length to extend over the box and part of a side thereof, whereby all of the flaps are covered and locked against accidental disengagement.

PETER ALBERT HOFFMAN.
